UNITED STATES PATENT OFFICE.

GUSTAV BERNHARD PETSCHE, OF PHILADELPHIA, PENNSYLVANIA, AS-SIGNOR TO THE SOUTHWARK FOUNDRY AND MACHINE COMPANY, OF SAME PLACE.

PUMP-VALVE-ACTUATING MECHANISM.

SPECIFICATION forming part of Letters Patent No. 657,671, dated September 11, 1900.

Application filed July 31, 1897. Serial No. 646,630. (No model.)

To all whom it may concern:

Be it known that I, GUSTAV BERNHARD PETSCHE, a subject of the Emperor of Germany, residing in the city and county of Philadelphia, in the State of Pennsylvania, have invented a certain new and useful Improvement 5 in Pump-Valve-Actuating Mechanism, of which the following is a true and exact description; reference being had to the accompanying drawings, which form a part thereof.

My invention relates to the construction and mode of operation of mechanism for actuating the delivery and suction valves of pumps, particularly of pumps used for liquids.

In another application filed by me July 31, 1897, Serial No. 646,629, I have described and claimed a new method and apparatus for actuating liquid pump-valves, in which I act upon the valves with intermittent yielding pressure applied at or slightly before the normal point in the motion of the plunger at which the valves should open or close and so proportioned with reference to the resistance to the motion of the valve developed by inequalities of pressure that the valve will move not only when the pressure upon its inner and outer faces is substantially balanced, but move them with great energy, thus insuring that the valves shall open or close at the critical moment and without imposing dangerous strains upon the valve-actuating mechanism. My said invention is especially designed with reference to the use of sliding laterally-moving valves, as by their use the obstruction to the passage of water through the valve which is met with in the ordinary type of clack-valve is avoided, with great gain to the efficiency of the pump.

My present invention embodies the essential features forming the subject-matter of my separate application mentioned above, but has especially for its object to provide for the operation of the valves through their lap by means of the fluid displaced by the plunger during that portion of its movement when the delivery-valve is closed and moving over its lap either in a direction to close or a direction to open, thus enabling the valves to open and close slightly after the flow of

fluid from the pump-chamber begins and 50 slightly before it ceases, which in the case of the use of slotted valves avoids one source of possible difficulty and in the case of any valve will be recognized as desirable, since it entirely obviates the risk of a return flow 55 through the valve while in the act of closing.

The nature of my improvements will be best understood as described in connection with the drawings, in which they are illustrated, and in which—

Figure 1 is an elevation, partly in section, of a pump provided with my improvements. Fig. 2 is a side elevation of the same apparatus, showing the valve-actuating cylinder in section. Figs. 3 and 4 are sectional views 65 of the pilot-valves. Fig. 5 is a diagram illustrating the action of the valve with respect to the flow of water and the motion of the valves; and Fig. 6 is a sectional elevation of a valve-actuating cylinder of the type 70 which I prefer to employ and which although embodying several features of importance invented by me is not herein claimed, as it forms in some features the subject-matter of my application for Letters Patent filed July 75 31, 1897, Serial No. 646,634, and in combination with the pump the subject-matter of other claims forming a part of my application filed July 31, 1897, Serial No. 646,629.

A and A' are the pump-chambers of a double-acting pump, A² indicating the delivery-ports, and A³ the suction-ports.

B is the suction-main, and B' the delivery-main.

C is the plunger, connecting by a piston-rod 85 C' with an engine, (indicated at C²), of which the main crank-shaft is shown at C³.

D D indicate the delivery-valves, which, as shown, are sliding gridiron-valves, preferably having an appreciable but slight freedom of 90 motion between their seats and their back bearings, (indicated at E'). A sixty-fourth of an inch I have found in practice to be sufficient, although slightly-greater play may be provided for without deleterious effects.

D' D' indicate the suction-valves, which are similar to the valves D.

D² D² indicate the valve-actuating rod, and

D³ D³ valve-rods connecting the delivery and suction valves in pairs—that is to say, the delivery-valve of the one cylinder with the suction-valve of the other cylinder—an arrangement which is appropriate, because these valves should move substantially at the same time both to open and close.

F F indicate valve-actuating cylinders, which I have shown in Figs. 1 and 2 in a simple and practical diagrammatic form. Preferably I construct the cylinders as indicated in Fig. 6.

G G indicate the pistons, working in the cylinders F and connected with the valve-stems D². From the opposite ends of the cylinder F lead ports F' F², communicating with the valve-chamber K, from which leads also an exhaust-passage F³ and to which leads a conduit H or H', communicating at its other end with one of the pump-chambers A or A', and preferably each of these conduits should be provided with a non-return valve, as indicated at h or h', for the purpose of preventing a reflux action of water in the conduit and of maintaining it at all times substantially full of fluid.

I is a valve working in the valve-chamber K, actuated by a positively-moving connection on the engine. As shown, it is connected, through a lever I', link J, and crank-connecting device J', with a link J², operated by an eccentric J³ on the main shaft of the engine, the link motion being such as will actuate the valve to connect one port, as F', with the pump-chamber through a conduit H or H' at or slightly before the time when the valve should move, the same motion of the pilot-valve connecting the other port F² with the exhaust-passage F³.

Referring now to the diagram Fig. 5, the distance from the point 3 to the point 6 indicates the total motion of the valve, of which the portion between the points 3 5 indicates the valve-lap. The line from 3 to 4 represents the total stroke of the pump, while the line rising in a curve from the point 3, running then in a straight line along the line 6 to 12 and falling in a curve to the point 4, represents approximately the relative motion of the valve with respect to the motion of the plunger, the true point of opening being at the point marked 7 and the true point of closing being at the point marked 8. It will be obvious that before the valve in opening has crossed the line 5 to 11 at the point 7 and that in closing after it has passed the point 8 on the said line the plunger will still force out of the cylinder a volume of water which is approximately represented at the beginning by the rectangle 3 5 7 9 and at the close of the stroke by the rectangle 10 8 11 4, but the pilot-valve I being opened at the points substantially corresponding with the points 7 and 8 the water passing from the pump-chamber before the valve-opening point passes to cylinder F and is utilized to partly open the valve, the capacity of the cylinder to receive

fluid being regulated by the amount of fluid expelled from the pump-chamber while the pump-valve is passing through its lap and so that said volume of fluid will move the valve through its lap. In the same way at the end of the stroke of the plunger the pilot-valve being opened substantially at the point 8 the fluid expelled from the pump-chamber during the time when the pump-valve is closing its lap will be utilized to move the already-closed valve through its lap.

Having now described my invention, what I claim as new, and desire to secure by Letters Patent, is—

1. In a pump the combination with a valve leading to or from the plunger-chamber of an actuating-cylinder, a piston therein operatively connected to the pump-valve, a conduit leading to the actuating-cylinder from the pump-chamber and a pilot-valve controlling the admission and exhaust of the fluid from the pump-cylinder to and from the actuating-cylinder the said actuating-cylinder being of a capacity to receive behind its piston the fluid forced out of the pump-chamber while the pump-valve is passing through its lap in opening and closing and the piston in the actuating-cylinder is making a corresponding part of its stroke.

2. In a pump the combination with a valve leading to or from the plunger-chamber of an actuating-cylinder, a piston therein operatively connected to the pump-valve, a conduit leading to the actuating-cylinder from the pump-chamber, a pilot-valve controlling the admission and exhaust of the fluid from the pump-cylinder to and from the actuating-cylinder and a non-return valve situated in the conduit leading from the pump-chamber to the actuating-cylinder the said actuating-cylinder being of a capacity to receive behind its piston the fluid forced out of the pump-chamber while the pump-valve is passing through its lap in opening and closing and the piston in the actuating-cylinder is making a corresponding part of its stroke.

3. In a pump the combination with a laterally-moving or slide valve leading to or from the plunger-chamber and having a slight freedom of movement to and from its seat, of an actuating-cylinder, a piston therein operatively connected to the pump-valve, a conduit leading to the actuating-cylinder from the pump-chamber and a pilot-valve controlling the admission and exhaust of the fluid from the pump-cylinder to and from the actuating-cylinder being of a capacity to receive behind its piston the fluid forced out of the pump-chamber while the pump-valve is passing through its lap in opening and closing and the piston in the actuating-cylinder is making a corresponding part of its stroke.

GUSTAV BERNHARD PETSCHE.
